[57] ABSTRACT

A collapsible garment hanger which opens to a triangular shape and collapses to a shortened and elongated shape. A telescopic lower member which locks in an extended position is joined through pivotal links to the opposite ends of an extendable top member which defines the two upper inclined shoulder sections of the hanger. These upper sections are pivotally attached the hanger hook to the center of the top member.

COLLAPSIBLE GARMENT HANGER

This invention relates to garment hangers, and more particularly, to a novel and improved collapsible garment hanger of simple and economical construction which opens to a sturdy, full-size garment hanger and which collapses to a compact and convenient size.

The standard rigid noncollapsible garment hanger, which is in widespread use, remains, more or less permanently in a closet, or on a coatrack. Normally, travelers rely on hangers of this type being present at their destination so that they can hang their garments. These hangers, however, are frequently not everywhere available. In many cases, it is desirable to have collapsible portable hangers in the form of a luggage accessory which can store compactly in a suitcase, or attache case, or in a form which can be kept in a small case and carried in a coat pocket or purse. Collapsible hangers per se are known in the prior art, but many of the collapsible hangers of the prior art have been too bulky for carrying in a coat pocket or purse, or tucking into a corner of an attache case, suitcase, or carrying with camping equipment. The most important drawback of these designs has been that they are too complicated and expensive to justify their manufacture. Collapsibility in the prior art hangers has been achieved in most cases by providing hinges and joints at points in the structure of the hanger where strength is most needed to support a garment. A common example is the use of a pivoting joint in the center of the bottom member. Features such as this have required the use of locks for holding the hanger in opened condition. These locks have been bulky, expensive to manufacture or inconvenient to use.

A principal objective of the present invention is to provide a collapsible hanger of simple and economical design which can be conveniently carried in a pocket or purse, and which can be carried in an attache case or suitcase without occupying any appreciable space.

The present invention is directed primarily toward providing a collapsible garment hanger which is exceedingly simple and economical to produce, and, accordingly, alternative embodiments of this invention can be made inexpensively by small-scale shop techniques and by mass production procedures. The hanger of the present invention collapses to a very flat, compact, elongated package, and opens quickly and easily by merely extending it longitudinally by moving the opposite ends of the members apart. The joints which provide the collapsibility do not appreciably contribute to the size of members which carry them, nor do they weaken the structure.

What is therefore provided by the present invention is a full-size hanger of the standard triangular shape having extendable top and bottom members. The bottom member forms the horizontal portion of the hanger which is used for hanging trousers and the like, and the top member forms the apex and the two inclined shoulder portions which are primarily used for hanging coats, dresses, and the like. The top and bottom members collapse to a generally parallel relationship and to approximately equal lengths to form a flat, easy-to-carry package about the size of a pocket slide rule. The top member is extendable to a greater total length than is the bottom member, and has a central pivot so that the top portion can swing upwardly to form the apex portion of the hanger. The hangers locks in an extended position, and the locking means is preferably carried by the bottom member to prevent it from contracting under compressive forces caused by the weight of a garment. The members are preferably made extendable through slot and key type fastening means where small-scale reproduction is anticipated, while other means, such as forming the bottom member of tubular or U-shaped sections slideable within one another are believed to be more practical and economical for large-scale production.

Other objects and advantages of the present invention will be more readily apparent from the following detailed description of the drawings, illustrating one preferred form of a collapsible hanger embodying principles of the present invention, in which:

FIG. 1 is an elevational view of the hanger, according to the present invention, in its fully opened condition;

FIG. 2 is an elevational view of the hanger of FIG. 1 in a partially collapsed condition;

FIG. 3 is an elevational view of the hanger of FIG. 1 in a completely collapsed condition;

5 FIG. 4 is an elevational view of alternative form of hanger according to the present invention in a collapsed condition;

FIG. 5 is an elevational view of the hanger FIG. 1 in a partially collapsed condition illustrating the relative extendability of the top and bottom members;

10 FIG. 6 is an exploded fragmentary prospective view of the locking means of the hanger FIG. 1;

FIG. 7 is a sectional view along line 7-7 of FIG. 1 illustrating the locking means in a locked condition;

15 FIG. 8 is a sectional view along line 8-8 of FIG. 2 illustrating a locking means in an unlocked condition; and

FIG. 9 is an elevational view of an alternative embodiment of the hanger of FIG. 3 in collapsed condition.

Referring first to FIG. 1, the hanger 10, shown in its fully

20 opened condition, includes a bottom member 11 and a top member 12. The top member 12 is pivotally attached at its opposite ends to the opposite ends of the bottom member 11, by pins 13 and 14. The bottom member 11 includes a pair of straight sections 17 and 18. The sections 17 and 18 are tele-

25 scopically connected at the joint 19 so as to be linearly extendable and retractable relative to each other. The telescopic joint 19, which can be made in many acceptable forms, is illustrated in the form preferred for manufacture in small or moderate quantities. This joint 19 includes a pair of longitudinally spaced keys 21 and 22, attached to the section 17, and which project through a longitudinal slot 23 of the member 18. The keys 21 and 22 have enlarged ends on the opposite side of the slot 23 from the section 17 to hold the sections 17 and 18 together. The keys 21 and 22 slide in the slot 23 to

30 form a slidably connection between the members 17 and 18 and thereby to telescopically join the members. The use of the two keys 21 and 22 makes the joint 19 a non-pivoting joint. The top member 12 is also comprised of two sections 31 and 32 which are joined in a pivotal and relatively longitudinally

35 extendable fashion by a key or pin 33 projecting through a pair of slots 35 and 36 respectively in the sections 31 and 32 to form a joint 34. The use of only one key 33 makes the joint 34 both pivoting and longitudinally extendable, instead of strictly telescoping as is joint 19 which is joined by two keys 21 and 22. A hook 36 is also pivotally mounted to the top member 12 by the pin 33. Where two slots 35 and 36 are shown in the top member 12, these slots being of equal length, a single slot of twice the length in only one of the sections 31 or 32 could be provided, however, greater strength can be achieved with less material when two slots of equal length are employed.

40 The sections 31 and 32 are provided with links 41 and 42 respectively in the ends thereof, these links are pivotally joined to the sections 31 and 32 by pins 43 and 44 respectively. The links 41 and 42 aid in the compact folding of the hanger 10 as is explained in more detail in connection with FIGS. 3 and 4 below. An economical alternative to these legs, and one almost as effective, is to provide fixed bends in place of links 41 and 42, as illustrated in FIG. 9, but these and other alternatives are also discussed in more detail below.

45 The bottom member 11 can also be formed of concentric tubes or of members of some other shape, and both the members 11 and 12 can be provided with additional telescoping joints to allow the hanger to collapse even more compactly.

50 Referring to FIG. 2, the collapsing of the hanger 10 is more clearly illustrated. As the bottom member 11 contracts, the sections 17 and 18 telescope relative to each other at the joint 19 and, the top member 12 contracts with the sections 31 and 32 linearly contracting at the joint 34 as the pin 33 moves in the slots 35 and 36.

55 The completely collapsed hanger 10 is shown in FIG. 3. The contracted top and bottom members 11 and 12 are parallel and the links 41 and 42 form angulated ends of the top member 12. The collapsed hanger forms a very compact, flat elongated package.

The angles formed between the section 31 and the link 41, and between the section 32 and the link 42, define the angles of which permanent bends 41A and 42A would be formed in the sections 31 and 32 if the links 41 and 42 were not used (FIG. 9). Whereas, the best exact angle for this purpose is generally determined by the thickness or width of the upper and lower members, by the relative position of the pins 13 and 14, and by the dimensions of the slots 23, 35 and 36, this angle will generally be an obtuse angle, that is, somewhat greater than 90°. Furthermore, this angle is generally required only when the top member falls against the upper surface of the bottom member 11 when the hanger is collapsed as illustrated in the embodiments shown in drawings. Alternatively, the top member can be so designed to fall behind the bottom member 11 when the hanger is collapsed and, when so designed, no angle portion would be required at all. However, because of the dimensions of the hook, no advantage is gained by this more compact folding of the top and bottom members 11 and 12. Another alternative, such as providing the bends in the bottom member 11 instead of the top member 12 is also possible. Where the links 41 and 42 are employed, a more compact collapsed shape is possible. The hanger may be designed to collapse to the shape illustrated in FIG. 4. Here the bottom member contracts an even greater amount to bring links 41 and 42 into a parallel relationship forming an elongated parallelogram.

The relative extendability of the bottom and top members 11 and 12 are best illustrated in FIG. 5. Here, the bottom member 11 is in its fully extended position, while the top member 12 is in a semicollapsed condition parallel to the bottom member 11 and not yet fully extended. The further extendability of the top member 12 allows the upper sections 31 and 32 to pivot relative to each other away from the bottom member 11 to form the apex of the triangle of the opened hanger, as illustrated by the arrows in FIG. 5.

FIGS. 6 through 8 show locking means which are provided to hold the hanger in its extended position. The locking means are located preferably at the telescopic joint 19 of the bottom member 11. Locking is achieved by rotating the key 21 through 90° in a circular hole 47 at the end of the slot 23. The hole 47 is of a diameter greater than the width of the slot 23. The key 21 is provided with an elongated neck 48 which has a length approximately equal to the diameter of the hole 47, and the width approximately equal to the width of the slot 23.

This is only one of many possible locking techniques which can be employed. Another simple alternative would be to provide a spring-biased detent mechanism which merely snaps into locking engagement when the bottom member 12 is brought to its extended position. This locking is generally necessary to prevent a bottom member from contracting under compressional forces caused by downward loading on the upper members 31 and 32 of the hanger 10. Alternatively, a lock could be located at the joint 34 to constrain the joint 34 to some minimum angle between the sections 31 and 32 of the top member 12.

What is described above is a full-size garment hanger which can be cheaply constructed and which folds into a useful and extremely compact form for carrying it in a suitcase, a coat pocket or a purse.

What is claimed is:

1. A collapsible garment hanger comprising:
a linearly extendable bottom member having at least two telescopically joined lower sections;
a linearly extendable top member having at least two pivotally joined upper sections, said top member having its opposite ends pivotally connected to the opposite ends

of said bottom member;
a hook pivotally attached to said top member near the center of said top member;
each of said members having an extended condition and a contracted condition, and each of said members being in said extended condition when said hanger is opened and in contracted condition when said hanger is collapsed;
when said hanger is opened, the total extended length of said top member being greater than the extended length of said bottom member with said upper sections being angulated to form a triangle with said bottom member;
when said hanger is collapsed, the contracted length of said top member being substantially equal to contracted length of said bottom member, with said upper sections being substantially aligned and parallel to said bottom member to form a shortened elongated shape; and
said hanger, when opened, having a width corresponding to the extended length of said lower member and, when collapsed, having a width less than its width when opened and corresponding to the contracted length of said lower member.

2. A collapsible hanger according to claim 1 wherein:
each of said upper sections has an angular bend formed therein near the end of said top member, whereby said hanger is substantially trapezoidal in shape when said hanger is collapsed.

3. A collapsible hanger according to claim 1 wherein:
said telescopic joining of said lower section comprises:
at least one of said joined sections having a longitudinal slot therein; and

a key extending through each of said lower sections and said slot for joining said sections together.

4. A collapsible hanger according to claim 1 wherein said pivotal joint of said upper sections comprises:
at least one of said upper sections having a longitudinal slot therein; and

a key extending through both of said upper sections and said slot for pivotally joining said upper sections together.

5. A collapsible hanger according to claim 4 wherein:
said key forms said pivotal attachment of said hook to said top member.

6. A collapsible hanger according to claim 1 further comprising:

a pair of links, each pivotally connected at one end thereof to different ends of said top member, and each pivotally connected at the other end thereof to different ends of said bottom member, said upper member, when contracted, being slightly shorter than said contracted lower member whereby said hanger is substantially trapezoidal in shape when collapsed.

7. A collapsible hanger according to claim 1 further comprising:
means for locking said lower member in an extended condition.

8. A collapsible hanger according to claim 7 wherein:
said locking means are located at said telescopic joint of said lower sections.

9. A collapsible hanger according to claim 1 further comprising:

a pair of links, each pivotally connected at one end thereof to different ends of said top member, and each pivotally connected at the other end thereof to different ends of said bottom member, and each forming mutually supplementary angles with said members when said hanger is collapsed, whereby said hanger is substantially a parallelogram in shape when collapsed.
